UNITED STATES PATENT OFFICE

138,516

DESIGN FOR A MAGNIFYING GLASS

John Michael Mangan, Wilkes-Barre, Pa., assignor of one-half to Joseph Ulevich, Plymouth, Pa.

Application June 13, 1944, Serial No. 113,978

Term of patent 14 years

(Cl. D57—1)

To all whom it may concern:

Be it known that I, John Michael Mangan, a citizen of the United States, residing at Wilkes-Barre, in the county of Luzerne and State of Pennsylvania, have invented a new, original, and ornamental Design for a Magnifying Glass, of which the following is a specification, reference being had to the accompanying drawing, forming part thereof.

Figure 1 is a top plan view of a magnifying glass showing my new design.

Figure 2 is an edge view thereof.

I claim:

The ornamental design for a magnifying glass as shown.

JOHN MICHAEL MANGAN.
